UNITED STATES PATENT OFFICE.

WILLIAM J. VAN KEUREN, OF HONESDALE, PENNSYLVANIA.

DESIGN FOR A BUTTON.

SPECIFICATION forming part of Design No. 21,843, dated September 6, 1892.

Application filed July 11, 1892. Serial No. 439,705. Term of patent 3½ years.

To all whom it may concern:

Be it known that I, WILLIAM J. VAN KEUREN, a citizen of the United States, residing at Honesdale, in the county of Wayne and State 5 of Pennsylvania, have invented and produced a new and original Design for Buttons; and I do hereby declare the following to be a full, clear, and exact description of the same, reference being had to the accompanying drawing, forming a part thereof.

My invention has reference to buttons to be used for campaign and similar purposes; and it consists of a new and original design therefor.

15 The leading feature of my design, which is shown in perspective in the accompanying drawing, consists of the representation of a

drum in perspective, and arranged above said drum is the representation of a drum-stick of proportionately large size.

The reference-letter *a* denotes the drum, and *b* is the drum-stick, formed integral therewith and arranged above in a horizontal line.

C is the shank of the button.

What I claim is—

The design for a button, as herein shown and described.

In testimony whereof I affix my signature in presence of two witnesses.

WILLIAM J. VAN KEUREN.
